CLAIM

The ornamental design for a lighting fixture, as shown and described.

DESCRIPTION

FIG. 1 is a top perspective view of a lighting fixture that has the design.

FIG. 2 is a side view of the lighting fixture of FIG. 1. The opposite side view is a mirror image of this view.

FIG. 3 is a bottom perspective view of the lighting fixture of FIG. 1.

FIG. 4 is a side view of the lighting fixture of FIG. 1, rotated 90 from the view of FIG. 2.

FIG. 5 is a bottom view of the lighting fixture of FIG. 1; and, FIG. 6 is a top view of the lighting fixture of FIG. 1.

The broken lines shown in FIG. 6 are for illustrative purposes only and form no part of the claimed design.
